UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

FEEDING MECHANISM FOR SEWING-MACHINES.

1,129,591.

Specification of Letters Patent. Patented Feb. 23, 1915.

Application filed September 10, 1907. Serial No. 392,209.

To all whom it may concern:

Be it known that I, LANSING ONDERDONK, a citizen of the United States, residing at New York city, in the county of New York, State of New York, have invented certain new and useful Improvements in Feeding Mechanism for Sewing-Machines, of which the following is a description, reference being had to the accompanying drawing, and to the letters and figures of reference marked thereon.

My invention relates to new and useful improvements in feeding mechanisms for sewing machines, and has for its object to provide a feeding mechanism which shall operate rapidly while in engagement with the material and which shall be positive in its movements.

My invention is especially adapted for use in connection with sewing machines having a work supporting post, although from certain aspects, the invention is adapted for use in connection with any type of sewing machines.

My invention consists in the parts, arrangements and improvements hereinafter shown, described and set forth in the claims.

In the drawings which illustrate one embodiment of my invention; Figure 1 is a sectional view of a work supporting post, showing my improved feeding mechanism in side elevation, certain parts of the machine being omitted for the sake of clearness; Fig. 2 is a sectional view showing the feeding mechanism as viewed from the front of the machine; Fig. 3 is a top plan view showing a work supporting post and the feed dogs, together with their carrier in top plan view; Fig. 4 is a detail of the feed regulating mechanism; Fig. 5 is a detail of the needle and feed dog.

The bed plate 1 has mounted on its forward end a work supporting post 2 upon which the material rests, during the sewing operation.

The shaft 3, mounted in the work support 1, is rotated continuously from any suitable means as for example, an upper rotary shaft such as shown in the applications above referred to. This shaft 3, extends through a bearing 4 and carries upon its forward end suitable eccentrics for operating the feeding mechanism. The feeding

mechanism comprises a feed bar 5, which is pivoted at its lower end 6 to a yoke 7, which is in turn pivoted at 8 to the bed plate of the machine. Said yoke 8, carries an arm 9, which is secured thereto by screws 10 and 11. The yoke 7, rests on the upper side of an eccentric 12, carried on the outer end of the shaft 3. The arm 9 extends underneath the eccentric 12, and by means of the screw 10, may be adjusted so as to be brought closely in contact with said eccentric 12.

The feed bar 5 is pivoted intermediate its ends at 13 to a link 14, which in turn is pivoted at 15 to a lever 16 which at its lower end, encircles an eccentric 17, mounted on the shaft 3. Said lever 16, intermediate 70 its ends, is pivoted at 18 to a link 19, which in turn is pivoted to a rock lever 20, at 19' mounted between the brackets 21, 21 preferably formed integral with the work supporting post 2 (see Fig. 2). Said rock lever 75 20 is secured to said brackets by a pivot bolt 23. A bracket 24 secured to the exterior portion of the work supporting post 2, has pivoted thereto a feed controlling arm 25. Said arm is pivoted to said bracket at 26 80 and carries a thumb nut 27, which is threaded on the outer end of said arm 25. The bracket 24 is provided with an outwardly extending portion 28, having its outer face formed concentrically with the 85 pivot 26 of the regulating arm 25. A washer, or clamping plate 29 is mounted on the outer end of said arm 25, and extends over the projecting portion 28 of the bracket 24. As the thumb nut 27 is turned down, 90 the washer 29 is brought into gripping contact with the portion 28 of the bracket and the regulating arm thereby held in its adjusted position. The regulating arm 25 is connected by means of a link 30 to the rock 95 lever 20. The feed bar 5 has formed integral therewith at its upper end arms 31 and 32 which project outwardly and upwardly forming a yoke which supports at its upper end a feed dog carrier 33, carrying feed dogs 34, 35. Said feed dog carrier is secured to said yoke by suitable screws 36, 37.

While I have shown two feed dogs in the present illustration of my invention, it is 105 obvious that a single feed dog may be used

in lieu thereof. By providing the feed bar with the yoke which supports the feed dogs, I form a clear space for mounting the loopers which coöperate with the needles. The 5 looper mechanism however, has been omitted for the sake of clearness. As the shaft 3 rotates, the eccentric 12 will cause the yoke 7 to oscillate about its pivot 8 and in turn give to the feed bar a rising and fall- 10 ing movement.

The eccentric 17 will cause the lever 16 to swing back and forth about the pivot 18 and also to raise and lower about the pivotal support 19' of the link 19 and these 15 movements of the lever 16 through the link 14 will cause the feed bar 5 to move back and forth.

The operation of my feeding mechanism is as follows: The eccentric 12 is so set on 20 the main shaft relative to the eccentric 17, that the feed dog is practically raised into engagement with the material, for the purpose of feeding the same before the eccentric 17 operates through the lever 16 to 25 move the feed dog to give thereto its feeding movements. As the eccentric 12 is rotated, the yoke 7 will be oscillated about its center 8. The tendency of the upward oscillation of 30 the yoke 7 about the center 8 is to move the lower end of the feed bar 31 to the right, as viewed in Fig. 1. At the same time, however, that the feed bar 31 is raised by said yoke, the link 14 is turned about its pivot center 15, and the resultant movement 35 in the feed bar is practically a bodily movement upward and slightly toward the front of the machine, into engagement with the material. As soon as the feed dog engages the material, the same is moved by the eccentric 17 to feed the work. There are three 40 essential elements which coöperate in giving to the feed dog its feeding movements: First, the eccentric 17 as it rotates with the shaft 3, tends to move the lower end of the lever 16 to the right, swinging the same about its fulcrum point 18. This movement of the lever 16 will give to the feed dog a slight feeding movement. Second, as the lever 16 is lifted by means of the eccentric 45 17, the link 19 is swung about its pivotal point 19', which carries the upper end of the lever 16 to the left, as viewed in Fig. 1, also giving to the feed dog a movement to feed the fabric. Third, as the lever 16 is 50 lifted by the eccentric 17, the link 14 is turned about the pivot 13, and this turning of the link 13, owing to the fact that the feed bar is practically stationary vertically at this time will tend to move the feed dog 55 to give still additional movement to said feed dog. These three active elements in the movement of the feed dog combine to give to said feed dog a very quick feeding movement, and likewise a very quick back- 60 ward movement, when disengaged from the 65

material. It will be noted that the eccentric 12 engages the yoke 6 at a greater distance from the pivotal point 8 in lifting the feed dog, than when lowering the feed dog. For this reason, the feed dog is slow 70 in its first movements into engagement with the fabric, and, therefore, the needle is given time to practically complete its stroke before the feed is brought into contact with the fabric and operated to feed the same. 75 When it is desired to regulate the length of the feeding stroke, the thumb nut 27 is loosened and the regulating arm 25 raised or lowered, and as the pivotal connection between the link 30 and the arm 25 is eccentric to the pivotal support 26 of said arm 25, the rock lever 20, will be moved about its pivotal support 23, and the position of the pivotal support 19' of the link 19 shifted. This shifting of the pivotal support 19', will 80 change the effective throw of the eccentric 17, and give, therefore, to the feed dog a greater or lesser movement to feed the material.

By the above arrangement of parts for 90 operating my feed dog, I have provided a feeding mechanism which operates very quickly. Furthermore, said feeding mechanism does not begin its feeding operation until the needle 37 is well above the work 95 plate, as shown in Fig. 5, wherein the extreme upper stroke of the needle is shown in dotted lines and said feed dog completes its feeding movement, as shown in dotted lines in said figure, by the time the needle 100 has moved from the position shown in full lines in said figure, to the extreme upper end of its stroke and back again to the full line position.

In one embodiment of my invention where 105 the needle had a reciprocation of $1\frac{1}{4}$ inches, I was enabled by my improved feed operating mechanism to move the feed dog the full length of the stitch desired, while the needle was moving from a position $\frac{1}{2}$ of an inch 110 from its highest point to its highest point and returning to a position $\frac{1}{2}$ of an inch below its highest point. This feeding of the fabric while the needle is well above the work support, allows me to operate upon 115 very thick material or to pass over heavy seams or the like in the material operated upon.

Having thus particularly described my invention, what I claim as new and desire 120 to secure by Letters Patent is:—

1. The combination with a bed plate and a work-supporting post extending vertically from one end thereof, of a feeding mechanism located in the work-supporting post including a feeding member, means for moving said feeding member up and down, and means for moving the same laterally comprising a lever, a link pivotally connected 125 at one end to said lever and at its other end 130

to said feeding member, means for vibrating said lever and a swinging fulcrum for said lever.

2. The combination with the bed plate and a work supporting post extending vertically from one end thereof of a feeding mechanism located in the work supporting post, including in combination a feeding member, means for moving said feeding member up and down, and means for moving the same laterally comprising a lever, means for connecting said lever to said feeding member, means for vibrating said lever, a swinging fulcrum for said lever, a pivotal support therefor, and means for shifting the position of the pivotal support of said swinging fulcrum.

3. The combination with the bed plate and a work supporting post extending vertically from one end thereof; of a feeding mechanism located in the work supporting post, including in combination a feeding member, means for raising and lowering the same, means for moving the same laterally comprising a lever, a link connecting one end of said lever to said feeding member, means for vibrating said lever and a swinging fulcrum for said lever.

4. The combination with the bed plate and a work supporting post extending vertically from one end thereof, of a feeding mechanism located in the work supporting post including in combination a feeding member, means for raising and lowering the same, means for moving the same laterally, comprising a lever, a link connecting one end of said lever to said feeding member, means for vibrating said lever and a swinging fulcrum for said lever, and means for shifting the position of the pivotal support of said swinging fulcrum.

5. The combination with a bed plate of a work supporting post extending vertically from one end thereof, a feeding member located in the work supporting post, means connected to the lower end of said feeding member for raising and lowering the same, means for moving said member laterally, comprising a lever, means for vibrating said lever and a link pivotally connected at one end to said lever and at its other end to said feeding member.

6. The combination with a bed plate of a work supporting post extending vertically from one end thereof, a feeding member located in the work supporting post, means connected to the lower end of said feeding member for raising and lowering the same, means for moving said member laterally comprising a lever, means for vibrating said lever and a link pivotally connected at one end to said lever and at its other end to said feeding member, and a shifting fulcrum for said lever.

65 7. The combination of a work supporting

post, a feeding member located therein, means connected to the lower end of said feeding member for raising and lowering the same, means for moving said member laterally, comprising a lever, means for vibrating said lever and a link connecting said lever to said feeding member, a shifting fulcrum for said lever, a pivotal support for said shifting fulcrum, and means for varying the position of the pivotal support for said shifting fulcrum.

70 8. The combination of a vertical work supporting post, a feeding member extending longitudinally thereof, a main shaft extending beneath said post, a yoke pivoted to said feeding member at its lower end and pivoted to the bed plate of the machine, an eccentric carried by said shaft for vibrating said yoke and means for moving said feed member laterally.

80 85 9. The combination of a vertical work supporting post, a feeding member extending longitudinally thereof, a main shaft extending beneath said post, a yoke pivoted to said feeding member at its lower end and pivoted to the bed plate of the machine, an eccentric carried by said shaft for vibrating said yoke, a lever supported within said post, means for connecting said lever to said feed member and means for vibrating said lever.

90 10. The combination of a work supporting post, a feeding member located therein, a main shaft, a yoke pivoted to said feeding member at its lower end, an eccentric carried by said shaft for vibrating said yoke, a lever supported within said post, means for connecting said lever to said feed member, means for vibrating said lever and a shifting fulcrum for said lever.

100 105 11. The combination of a work supporting post, a feeding member located therein, a main shaft, a yoke pivoted to said feeding member at its lower end, an eccentric carried by said shaft for vibrating said yoke, a lever supported within said post, means for connecting said lever to said feed member, means for vibrating said lever, a shifting fulcrum for said lever, and means for adjusting the pivotal support of said shifting fulcrum.

110 115 120 125 130 12. A sewing machine including in combination a work supporting post, a feeding member located therein, a main shaft, a yoke pivotally supported beneath said work supporting post, means for connecting said yoke to said feeding member, an eccentric carried by said shaft for vibrating said yoke, a lever, means for connecting said lever to said feeding member, means for vibrating said lever, a link pivoted to said lever between its ends, a rock lever to which said link is pivoted and means for adjusting said rock lever and holding the same in its adjusted positions.

13. A sewing machine including in combination a work supporting post, a feeding member located therein, a main shaft, a yoke pivotally supported beneath said work supporting post, means for connecting said yoke to said feeding member, an eccentric carried by said shaft for vibrating said yoke, a link for connecting said lever to said feeding member, means for vibrating said lever, 5 a link pivoted to said lever between its ends, a rock lever to which said last named link is pivoted, a regulating arm pivoted to the work supporting post, a link connecting said regulating arm to said rock lever and means 10 for holding said regulating arm in its adjusted positions.
14. A sewing machine including in combination a bed plate, a work support rising therefrom, a feeding member within said 20 work support, means for operating said feeding member, and means for regulating the throw of said feeding member including a rock lever, a bracket secured to said work supporting post, a regulating arm pivoted to said bracket, and a link between said regulating arm and said rock lever.
15. A sewing machine including in combination a bed plate, a work support rising therefrom, a feeding member within said 30 work supporting means for operating said feeding member, means for regulating the throw of said feeding member, including a rock lever, a bracket secured to said work supporting post, a regulating arm pivoted to said bracket, a link between said regulating arm and rock lever, a clamping nut carried by said regulating arm, and co-operating with said bracket for holding the same in adjusted positions.
- 40 16. A sewing machine including in combination a bed plate, a work supporting post rising therefrom, feeding mechanism within said work supporting post, means for regulating the throw of said mechanisms, comprising a bracket secured to said work supporting post, and having a projection extending therefrom, a regulating arm pivoted to said bracket, a clamping collar mounted on said arm and extending over
- 50 said projection, and a clamping screw for forcing said clamping collar into contact with said projection.
17. A sewing machine including in combination a work support, a vertically arranged feeding member located beneath said work support, a lever extending substantially parallel with said feeding member for moving said feeding member back and forth, a swinging link on which said lever is fulcrumed, a link between said feeding member and said lever and means for operating said lever to swing the same about its fulcrum on said link, and also to swing said link carrying the fulcrum of said lever.
18. A sewing machine including in combination a work support, a vertically arranged feeding member located beneath said work support, a lever extending substantially parallel with said feeding member for moving said feeding member back and forth, a swinging link on which said lever is fulcrumed, a link between said feeding member and said lever, and means for operating said lever to swing the same about its fulcrum on said link and also to swing said 75 link carrying the fulcrum of said lever, and means for raising and lowering said feed member.
19. A feeding mechanism comprising a substantially vertical feed bar carrying a 80 feed dog on the upper end thereof and means for moving the feed bar laterally at the end thereof adjacent the feed dog for giving feeding movements to the feed dog, means for moving the feed bar longitudinally for causing the feed dog to engage the fabric, said last named means including a yoke pivoted at one end to the bed plate of the machine and at its other end to the lower end of the feed bar, and an eccentric for 85 engaging and oscillating said yoke.
- In testimony whereof I affix my signature, in presence of two witnesses.
